UNITED STATES PATENT OFFICE.

JOHN H. TAYLOR, OF NORMANDY, TENNESSEE.

HAND-CAR.

No. 847,030.

Specification of Letters Patent.

Patented March 12, 1907.

Application filed December 28, 1906. Serial No. 349,909.

To all whom it may concern:

Be it known that I, JOHN H. TAYLOR, a citizen of the United States, residing at Normandy, in the county of Bedford, State of Tennessee, have invented certain new and useful Improvements in Hand-Cars; and I do hereby declare the following to be a full, clear, and exact description of the invention, such as will enable others skilled in the art to which it appertains to make and use the same.

This invention has relation to hand-cars for railways; and it has for its object the provision of improvements in the propelling mechanism operable from the platform of the car when the latter is employed for quick transportation, whereby said propelling mechanism maybe disconnected from the axles and wheels, so that the latter may be free to run, as on a downgrade, or allow the car to be employed as a "push-car" in transporting material and tools about in the performance of section and other work.

The nature of the invention is fully ascertainable from the annexed drawings, forming a part of this specification, in view of which it will first be described with respect to its construction and mode of operation and then be pointed out in the claims.

Of the said drawings, Figure 1 is a sectional side elevation. Fig. 2 is a plan of the car inverted, showing the propelling-gear in mesh with the driven pinion on the axle. Fig. 3 is a view similar to Fig. 2, but representing the propelling-gear as out of mesh with the axle-pinion. Fig. 4 is a sectional view in the plane of the axle and axis of the propelling-gear.

Similar numerals of reference designate similar parts or features, as the case may be, wherever they occur.

In the drawings, 10 designates the platform, which on its under side supports the journal-boxes for the axles 11 of the wheels 12.

The front axle has a pinion 13 secured to it, with which meshes the drive-gear 14. The latter is provided with a wrist-pin 15, with which the lower end of a pitman 16 is connected, said pitman extending up through an opening in the platform and being pivotally connected at its upper end with one end of a rock-bar 17, pivoted on a cross-bar 18, having bearings in the uprights 19, secured at their lower ends to the platform of the car. The other end of the rock-bar is connected with the lower end of a pitman 20, the upper

end of which is pivoted on an arm of the hand-operating lever 21, which operates on a cross-shaft 22, supported in the upper ends of the said uprights.

By the means described a hand-car is provided that may be propelled on a railway-track by a person or persons standing on the platform and operating the hand-lever. It is sometimes desired, however, as when the car is running downgrade or when it is wanted to use the device as a push-car, that the driving means should be disconnected from the axle, so as to leave the latter as free from impediments as possible, and it is to this end that my invention is directed.

The drive-gear 14 has its axle 23 extended from one side only, and the said axle is journaled on a box or bearing 24, having a pivot-bolt 25 extending from its upper side through one of the longitudinal beams 26 of the car, a bushing surrounding the pivot-bolt for the usual purpose.

A keeper 27 in the form of a plate, having its central portion offset to fit upon the bottom of the box, is secured at its ends to the beam 26 to hold the bearing in place. The latter is provided on its upper side with an extension 28, which at its outer end has a right-angular downwardly-extended lug or ear in which the outer end of the axle turns and is supported. The said box or bearing 24 has a pin or projection 29 extending laterally therefrom, on which the lower end of a lever 30 is connected. The said lever is fulcrumed on a stud or pin 31, supported on the car-platform, and extends up to one side of the hand-lever in position where it can be readily reached by a person on the platform to move it, and so shift the bearing 24 for the axle of the driving-gear, that the latter may be moved out of or into engagement with the pinion 13, disconnecting or connecting the hand-car-operating means from or with the axle and wheels.

By the means described, which are simple in construction and efficient and convenient in use, the car is convertible instantly from a hand to push car, and vice versa, and when running as a hand-car on a downgrade the operating means can be detached, so as to permit the car to "coast" with freedom, if desired.

Of course the box for the axle of the driving-gear might well be supported vertically by its pivot-bolt, avoiding any necessity of the keeper-plate 27; but ordinarily a device

performing the functions of the latter is desirable.

What is claimed is—

1. In a hand-car, the combination with the driven axle and its pinion, of the drive-gear and its axle, a pivotally-supported bearing for the axle of the drive-gear, and a lever pivotally connected with the said bearing to move it on its pivot and disconnect or connect the driving-gear from the said pinion.
2. In a hand-car the combination with the driven axle and its pinion, of the drive-gear,

means for operating it, a pivoted bearing for the axle, means for supporting the bearing, and a lever pivotally connected with said bearing to move it on its pivot and disconnect or connect the driving-gear from the said pinion. 15

In testimony whereof I affix my signature in presence of two witnesses.

JOHN H. TAYLOR.
